UNITED STATES PATENT OFFICE.

HARVEY L. HEALD, OF GRANVILLE CENTRE, PENNSYLVANIA.

DESIGN FOR A CHEEK-PIECE.

SPECIFICATION forming part of Design No. 22,205, dated February 7, 1893.

Application filed January 11, 1893. Serial No. 458,092. Term of patent 7 years.

To all whom it may concern:

Be it known that I, HARVEY L. HEALD, of Granville Centre, in the county of Bradford, in the State of Pennsylvania, have invented 5 a new Design for Cheek-Pieces, of which the following, taken in connection with the accompanying drawing, is a full, clear, and exact description.

In the drawing I show a top-plan view of 10 my design cheek-piece.

The leading features of my design consist in the regularly curved contour and the irregularly divided open-center.

15 A, is the cheek piece which is circular in its general contour; and —1— are curved openings or recesses in the edges thereof, conform-

ing to the general outline of the outer edge of the body; and —2— and —3— are bars extending across the open center, breaking it somewhat irregularly; thus presenting to the eye the combined effects of a smooth circular contour and an irregular center.

What I claim and desire to secure by Letters Patent is:

The design for a cheek-piece, substantially 25 as herein described and shown.

In witness whereof I have hereunto set my hand this 19th day of December, 1892.

HARVEY L. HEALD.

In presence of—

A. S. HOOKER,
C. H. BLACKWELL.
